UNITED STATES PATENT OFFICE.

LOUIS R. FORD, OF NEW YORK, N. Y., ASSIGNOR TO WORTHINGTON PUMP AND MACHINERY CORPORATION, OF NEW YORK, N. Y., A CORPORATION OF VIRGINIA.

PISTON-COOLING ASSEMBLY.

Application filed June 14, 1921. Serial No. 477,478.

To all whom it may concern:

Be it known that I, LOUIS R. FORD, a citizen of the United States, residing at New York city, county of Kings, and State of New York, have invented certain new and useful Improvements in Piston-Cooling Assemblies, fully described and represented in the following specification and the accompanying drawings, forming a part of the same.

This invention relates to an improvement in piston cooling assembly for internal combustion engines.

The invention aims especially to prevent the objectionable feature of splashing of cooling liquid from the telescoping tubes adapted to circulate the cooling liquid. Difficulty has heretofore been experienced with such cooling systems, due to the fact that the splash hood over the end of the stationary tube must necessarily be provided with large clearance around the reciprocating tube to prevent rubbing against the hood on any sideplay or misalignment of the tubes due to wear of the engine parts or otherwise, such clearance also being necessary to prevent bending or breaking of the tubes in case of misalignment. In this character of apparatus a large amount of cooling liquid adheres to the outside of the reciprocating tube and is carried up with it beyond the splash hood and, on the sudden reversal of the piston to which such reciprocating tube is secured, this liquid is jerked therefrom, due to the inertia of the upwardly moving liquid with respect to the tube, with the result that the cooling liquid is sprayed into the cylinder base or over the piston rods. The present invention overcomes this difficulty by simple, efficient and durable means.

For a full understanding of the invention, a construction embodying the same in a preferred form, will now be described in connection with the accompanying drawings, and the novel features thereof then be pointed out in the claims.

In the drawings—

Figure 1 is an elevation, partly in section, of an engine power cylinder, the member or partition separating it from the crank pit, and the general location of the present invention with respect to such parts;

Figure 2 is an enlarged central section of a portion of an engine piston, showing the

telescoping tubes, splashhood and sealing ring therein;

Figure 3 is a plan view of a preferred form of combined packing and wiping ring, and

Figure 4 is a section thereof on the line 4—4 of Fig. 3.

Referring now to the drawings, and especially to Fig. 2, the engine piston A to be cooled has secured thereto in the usual manner a cooling liquid circulating tube 10 adapted to reciprocate in a tube 11 supported by the member B. Over the top of the stationary tube 11, and preferably also secured to the member B in any convenient manner, is a splash hood 1, the orifice 2 in the top of which is sufficiently large to provide ample clearance around the tube 10 in the event of any sideplay of such tube due to wear or otherwise of the engine parts.

In order to prevent cooling liquid adhering to the outside of the tube 10 being carried up beyond the splash hood 1, through the clearance orifice 2 in the top thereof, with the consequences above stated, there is provided within the hood 1 and mounted on the tube 10 a combined packing and wiping ring 3, which is of smaller diameter than the inside diameter of the hood to allow for movement sidewise as above explained. The ring 3 is preferably made of brass and in two parts, secured together as shown or in any other suitable manner, the orifice in such ring being slightly larger than the diameter of the piston 10, and such ring is also preferably provided with an interior groove 80 for retaining suitable packing. This packing is preferably of braided flax, cut square in cross-section as shown at 4, Fig. 4. This material has been found to be durable and to maintain a tight fit around the tube 10, which is necessary for efficient operation of the device. The splash hood chamber is preferably enlarged by making the hole in the member B through which the tube 11 passes larger than such tube, so as to form 95 an annular catch basin 5. The tube 11 is also provided with a flange 6 having an annular chamber 7 therein corresponding in size to the hole in the member B and registering therewith, and is tapped at 8 by a 105 pipe leading to any desired point, to permit drainage of the catch basin 5.

It will be obvious from the foregoing that,

as the tube 10 is withdrawn from the tube 11 on the upward stroke of the piston A, liquid adhering to the exterior of the tube 10 will be wiped therefrom by the combined packing and wiping ring 3 and, as such ring fits the tube 10 snugly, it will be carried against the top of the splash hood 1 on slight upward movement of the tube, thereby effectually sealing the orifice 2 against passage of liquid wiped off the tube 10 by the ring and collecting in the splash hood 1, to be drained therefrom through outlet 8 leading to any desired point. To prevent the ring 3 from having too great a movement within the hood 1, there are provided a plurality of lugs 9 on which such ring seats during the downstroke of the piston. This effectually prevents battering of the ring against the tops of the splash hood and tube 11, respectively, as would be the case if it had a long range of movement.

It will be understood that various changes may be made in the construction and still be within the scope of the appended claims.

25. What is claimed is:

1. In a piston cooling assembly for engines, the combination with the reciprocating cooling water tube thereof, of a hooded

chamber having an orifice through which the tube passes, and means in said chamber 30 for simultaneously wiping the exterior of the tube and closing the hood orifice as said tube is withdrawn from the chamber.

2. In a piston cooling assembly for engines, the combination with the reciprocating and stationary telescoping tubes thereof, of a hood having an orifice through which the reciprocating tube passes, and a wiping and sealing ring carried by the reciprocating tube and confined in said hood for closing 35 said orifice as the reciprocating tube is withdrawn from said hood.

3. In a piston cooling assembly for engines, the combination with the reciprocating and stationary telescoping tubes thereof, 40 of a hood having an orifice through which the reciprocating tube passes, a wiping and sealing ring carried by and movable on the reciprocating tube and confined in said hood for closing said orifice as the reciprocating 45 tube is withdrawn from the hood, and a support within said hood for limiting the movement of said ring.

In testimony whereof, I have hereunto set my hand.

LOUIS R. FORD.
